UNITED STATES PATENT OFFICE.

EDWARD M. HARBERTSON, OF LOS ANGELES, CALIFORNIA.

SLIP-SLEEVE VALVE.

Application filed May 18, 1923. Serial No. 639,987.

To all whom it may concern:

Be it known that I, EDWARD M. HARBERTSON, a citizen of the United States, residing at Los Angeles, in the county of Los Angeles and State of California, have invented new and useful Improvements in Slip-Sleeve Valves, of which the following is a specification.

My present invention being a slip sleeve valve, it is an object of this invention to replace the usual cap at the end of a drain pipe, or the like, by a construction which may present substantially the appearance of a cap upon a nipple, and may nevertheless 10 comprise means for directing the outflow of a drained liquid in a desired direction.

It is a further object of this invention to provide means of the character referred to which may cooperate in guiding a cap during the seating of the same and which may also comprise a gasket or gaskets arranged effectively to prevent leakage when said cap is seated; and my preferred construction for the purpose referred to may comprise 20 a cap swivelled to a laterally apertured sleeve in such a manner as to retain a plurality of relatively movable gaskets in place, means being optionally provided to hinder or prevent the complete separation of the parts referred to, with consequent risk of 25 loss or misplacement.

Other object of my invention will appear from the following description of a preferred embodiment thereof and from the appended claims, taken in connection with the accompanying drawings, in which

Figure 1 is a vertical section through one form of valve embodying my invention and showing the valve as closed.

Fig. 2 is a corresponding view, the valve being shown as open, and a modified form of sleeve-retaining means being shown.

Fig. 3 is an elevation showing one form of cap and sleeve which may be employed in my novel valve.

Referring in detail to the parts of that form of my invention shown in Figures 1 and 3, 1 may be the bottom of any container with which the nipple or outlet pipe 2 may be connected, this pipe being secured by nuts 3, 4 and washers 5, 6, in a well known manner, and provided with a cap 7.

It being obvious that, when only the parts referred to are employed, the removal of the cap 7 must occasion a sudden exit and splashing of the liquid retained thereby,

this liquid being often of a greasy or disagreeable character, I associate with the said cap 7 a sleeve 8, provided with a lateral aperture 9, and adapted to fit and extend upward to any suitable distance within the outlet pipe 2; and, in order that the flow of liquid through the aperture 9 shall occur in a known or predetermined direction, I prefer to provide for a relative movement 60 between the cap 7 and the sleeve 8, and to provide also a means for restraining or preventing the rotation of the sleeve 8 within the pipe 2.

In order to hold the sleeve 8 against rotation in the pipe 2, I may kerf the upper portion of the same in, for example, the manner shown at 10 in Figure 1, whereby the imparting of a slight outward bend to the resilient section 11 may serve, by its frictional engagement with the interior of the pipe 2, to retain the mentioned parts against relative rotation. Alternatively, I may employ, for this purpose, a construction such as is shown in Figure 2, in which the sleeve 8^a is provided with a longitudinal slot 10^a, through which may project the inner end of a screw 12, seated in the pipe 2^a, and serving not only to retain the sleeve 8^a against rotation, but also to limit the descent 85 thereof when the valve is opened, in the manner shown in Figure 2. When this construction is employed, the user of my valve may know that the exit of fluid from the valve will occur at the opposite side of the 90 pipe 2^a from that upon which the head of the screw 12 appears.

In order to provide a tight joint between the cap 7 and the pipe upon which it may be employed, and at the same time permit 95 of a relative rotation between the sleeve 8 or 8^a and the said cap, as is necessary in applying or removing said cap, any suitable means may be employed; and for this purpose I prefer to provide a swivel connection comprising a plate 13, shown as secured by screws 14, extending through the cap 7 and also through a cupped gasket 15, secured by said screws and plate; the mentioned swivel connection comprising also a 100 pivot screw 16, seated in an inclined plug 17, secured in the lower end of the sleeve 8 or 8^a, said screw extending through a central aperture in the plate 13, and being provided with a head 18 adapted to engage the 105 lower surface of said plate, and being provided also with an adjustable nut 19 and a

washer 20, adapted to retain the packing 21; it being understood that the packing 21 is normally secured against rotation and adapted to contact with the inner surface 5 of the pipe 2 or 2^a while the gasket 15 is adapted to rotate with the cap 7 and to contact with the lower end of the said pipe, when my valve is closed, in the manner best shown in Figure 1.

10 From the foregoing it will be obvious that I have provided a simple and effective slip sleeve valve, especially suitable for use in connection with drain or cleanout openings, and comprising means whereby a tight 15 closure may be effected when desired, and whereby an outflow of liquid may be turned in a desired direction, in order to avoid soiling the hands or clothing of the user of my valve; and also that I have provided a slip 20 sleeve valve which may be manufactured and sold at a very moderate cost, it being, moreover, easily possible either to manufacture and market complete valves of the character described or to provide existing outlets 25 with caps and sleeves of the character herein described.

Although I have herein described but one complete embodiment and a modification thereof, it will be understood that various 30 features thereof might be independently employed, and also that various modifications might be made therein without departure from the spirit and scope of my invention, as the same is indicated above and in the 35 following claims.

What I claim is:

1. In a slip sleeve valve, a fixed outlet pipe, a cap therefor, and an apertured sleeve secured to said cap and extending 40 into said pipe, said sleeve being provided with a gasket secured at the end thereof and adapted to contact with the interior of said pipe.
2. In a slip sleeve valve, a fixed outlet 45 pipe, a cap therefor, and an apertured sleeve secured to said cap and extending into said pipe, said cap being provided with a gasket secured therein by a plate.

3. In a slip sleeve valve, a fixed outlet pipe, a cap therefor, and an apertured 50 sleeve secured to said cap and extending into said pipe, said cap being provided with a gasket secured therein by a plate provided with a central aperture.

4. In a slip sleeve valve, a fixed outlet 55 pipe, a cap therefor, and an apertured sleeve secured to said cap and extending into said pipe, said cap being provided with a gasket secured therein by a plate 60 provided with a central aperture and secured to said cap.

5. In a slip sleeve valve, a fixed outlet 65 pipe, a cap therefor, and an apertured sleeve secured to said cap and extending into said pipe, said cap being provided with a gasket secured therein by a plate 70 provided with a central aperture adapted to receive a pivot screw.

6. In a slip sleeve valve, a fixed outlet 75 pipe, a cap therefor, and an apertured sleeve secured to said cap and extending into said pipe, said cap being provided with a gasket secured therein by a plate provided with a central aperture adapted to receive a pivot screw extending into an inclined plug.

7. In a slip sleeve valve, a fixed outlet 80 pipe, a cap therefor, and an apertured sleeve secured to said cap and extending into said pipe, said cap being provided with a gasket secured therein by a plate provided with a central aperture adapted to receive a pivot screw extending into an inclined plug secured in said sleeve.

8. In a slip sleeve valve, a fixed outlet 85 pipe, a cap therefor, and an apertured sleeve secured to said cap and extending into said pipe, said cap being provided with a gasket secured therein by a plate 90 provided with a central aperture adapted to receive a pivot screw extending through an additional gasket.

In testimony whereof I have signed my name to this specification.

EDWARD M. HARBERSON.
